UNITED STATES PATENT OFFICE.

GEORGE B. KEPLINGER, OF CHICAGO, ILLINOIS.

CALENDAR.

SPECIFICATION forming part of Letters Patent No. 758,758, dated May 3, 1904.

Application filed October 17, 1902. Serial No. 127,639. (No model.)

To all whom it may concern:

Be it known that I, GEORGE B. KEPLINGER, a citizen of the United States, residing at Chicago, in the county of Cook and State of Illinois, have invented certain new and useful Improvements in Calendars, (Case No. 3,) of which the following is a specification.

My invention relates to calendars, and the object is to provide a simple and novel form 10 of calendar that may be carried in the pocket of the user and that will enable the user to readily determine the day of the month and the day of the week upon which any given date in any month fell or will fall.

15 In the accompanying drawings, which illustrate my invention, Figure 1 is a plan view of a calendar constructed in accordance with my invention. Fig. 2 is a sectional view on the line 2-2 of Fig. 1. Fig. 3 is a detail plan 20 view of the base-plate, and Fig. 4 is a detail plan view of the rotating disk.

Referring to the drawings, the reference-letter A denotes a plate of suitable material, preferably metal, which may be of any suitable size and shape and preferably is in the 25 form of a circular disk of such size as conveniently to be carried in the pocket of a waistcoat. The plate A is the base-plate upon which the other parts are assembled and carried. The plate is provided in its body with a central circular depression or well a, provided by stamping the metal down from its front face, and has a band a' surrounding the well. The outer edge of the plate is provided 30 with a flange a'' of greater depth than the well. The well receives a rotatable disk B, which is provided adjacent its edge with a line of figures from the numeral "1" (preferably represented by an arrow or pointer) to 35 "31," designating the days of the month. The disk is of any suitable material, such as celluloid, and is rotatably confined within the well by any suitable means. In practice I employ for this purpose a ring a'' of suitable 40 material, such as celluloid, whose inner edge overhangs the disk B and is turned down, as at a', to rest upon the same. The ring a'' is supported upon the raised band a' of the plate A by means of turning its outer edge over 45 the flange a'' of the plate, to which it is clamped 50

or crimped in a suitable press. The flange is caused to clamp over the edge of a suitable part C, which may be any suitable disk carrying advertising matter or may be the rim of a looking-glass. The outer edge of the ring 55 a'' is clamped between the flange a' and the part C.

Adjacent its inner edge the ring a'' is provided with a series of letters, indicating the sequence of the days of the week, and five 60 sets of these letters are provided, so that when the dial or disk is set with the arrow on the numeral "1," indicating the first day of any month, at any letter, indicating the day of the week upon which the chosen month begins, each of the succeeding numerals up to the number of days contained in that month will be in register with a letter indicating the corresponding day of the week. By this means 65 a calendar for that month is provided.

The ring a'' in practice may be made wide enough to accommodate any desired printed matter, such as an advertisement, in addition to the letters indicating the days of the week.

By reason of the letters indicating the days 70 running continuously for five weeks or being greater in number than days in the longest month the user may readily determine the day upon which the next succeeding month will begin and set the arrow for the numeral "1" 75 at the letter following the letter corresponding to the last day of the preceding month. By this means the calendar becomes perpetual.

In order that the user may determine any 80 day of the week corresponding with a past or future date of any month, it is only necessary for him to set the arrow at the day upon which the month began, and the calendar then denotes the days of the week upon which different dates in that month fell or will fall. For 85 expediting the work in this respect a directory stating the day of the week upon which the several months began may be provided. This is shown clearly in Fig. 1, where the initial 90 days of the various months of the current year 95 are stated. It is understood that these may be multiplied for any number of years, the purpose being to provide a directory of these dates, whereby the calendar may be utilized for one or a series of years. The device may 100

conveniently carry directions for the use of the calendar, such as are indicated in the drawings.

Having described my invention, I claim—

- 5 1. A calendar comprising a plate having a well and a band surrounding the well and provided with a flange at its edge, a rotatable disk in the well, and a ring projecting at its inner edge over the disk and having its outer edge engaged with the said flange, the said disk and ring being provided with complementary symbols designating the days of the week and month.
- 15 2. A calendar comprising a plate having a central circular well, a band about the well and provided with a flange, a disk rotatably

mounted in the well and provided on its margin with numerals equal to the number of days in the longest month, a ring on the band having its inner edge projecting over the edge of the disk and provided with five sets of letters arranged in the order of the days of the week, the outer edge of the ring being clamped to the flange, and the disk bearing a directory indicating the days of the week upon which the months of any year or series of years begin.

In testimony whereof I affix my signature in presence of two witnesses.

GEORGE B. KEPLINGER.
